CARRIAGE SHIFT FOR TYPEWRITERS

Roy C. Masters, Chicago, Ill., assignor to Ferdinand Enslein, Chicago, Ill.

Application March 24, 1933, Serial No. 662,580

1 Claim. (Cl. 197—65)

The present invention relates to new and useful improvements in carriage shifts for typewriters, and more particularly to a foot operated shift.

One of the objects of this invention is to provide a device for shifting typewriter carriages which can be readily operated by the person using the typewriter, whereby the operator can use his foot to shift the carriage and increase 10 the speed in using the machine.

It often occurs that a person using the touch system of manipulating the keys of a typewriter will not bring his fingers back to rest upon the proper keys after shifting the carriage by hand, 15 thus causing the operator to strike the wrong keys.

Another object of this invention is to save the time of the operator. When in the course of copying, it shifts the carriage of the typewriter 20 without compelling the operator to remove the eyes from the copy, and obviating the necessity of re-locating the sequence of the last word prior to the shifting of the carriage.

Another object of the invention is to provide 25 a carriage shifting device of the above character which can be readily operated by the foot so that the person using the typewriter will not have to remove his hands from the key-board.

A further object of the invention is the provision of a carriage shifting device which can be 30 easily attached to a typewriting machine for shifting the carriage, either from the right or the left side of the carriage, according to the type of machine to which the device is to be applied, or the wish of the operator.

With the above and other objects in view, the invention consists in the novel features of construction, the combination and arrangement of parts hereinafter more fully set forth, pointed 40 out in the claims and shown in the accompanying drawings, in which

Fig. 1 is a top plan view showing my device applied to a typewriting machine and looking in the direction of the arrows on the line 1—1 of 45 Fig. 2.

Fig. 2 is a front elevation.

Fig. 3 is a side elevation looking in the direction of the arrows on the line 3—3 of Fig. 1.

Fig. 4 is a side elevation of a link type of connecting arm to attach the device to the carriage.

Fig. 5 is a side elevation of a modified type of foot engaging member.

Fig. 6 is a cross sectional view on the line 6—6 of Fig. 5, looking in the direction of the arrows.

Fig. 7 is a sectional view on the line 7—7 of Fig. 3, and

Fig. 8 is a side elevation of the foot engaging member looking in the direction of the arrows on the line 8—8 of Fig. 7.

In the accompanying drawings it will be noted that in Figs. 1 to 3, I have illustrated my device as applied to a conventional type of typewriting machine, which is shown in dotted lines and includes the usual carriage 1.

The typewriting machine usually rests upon a desk or other support as shown at 2 and the support rests upon the floor, which in the present instance is indicated at 3. Secured to the floor 10 3 at one side of the machine is a base member 4 upon which is rotatably supported a drum 5.

Attached to the drum and extending upwardly therefrom, is a sectional adjustable standard, which includes the lower section 6, the upper end of which is hollow to receive the lower end of 20 the upper section 7. The upper section 7, is held in adjusted position relative the lower section by means of the set screws 8.

The upper section 7 passes through a guide bracket 9 which is secured to the desk 2 by means 25 of a clamping screw 10. An adjustable collar 11 on the section 7 is secured in place by means of a set screw 12, and bears against the bracket 9 for holding the section 7 against downward movement.

The upper end of the section 7 is extended laterally to form a crank arm 13, having a hollow outer end to receive the inner end of an adjustable finger 14. The finger 14 is held in adjusted positions by means of a set screw 15. The 35 finger has attached to its outer end a pliable connecting member 16, which in turn is attached to a pin 17, at one end of the paper carriage 1.

Extending around the drum 5 for a greater portion of its circumference is a flexible belt 18, one 40 end of which is secured to the drum, while the other end is connected to the upwardly extending arm 19, of a pivoted crank, the other arm 20, of which extends laterally from the bracket 21. The crank is pivoted to the bracket 21 by means 45 of the bolt 22, while the bracket is secured to one leg of the desk as shown in Fig. 7.

Attached to the arm 20 of the crank is a treadle 23 designed to be engaged by the toe portion of the foot of the operator, whereby downward 50 pressure on the treadle will rotate the drum and standard for swinging the finger 14 in the arc of a circle and shift the carriage 1 to its normal starting position so that the carriage can be readily shifted without the operator re- 55

moving his fingers from the proper keys of the key-board.

In Fig. 4 I have illustrated one form of connecting member 16, which includes a plurality of pivotally connected sections 16, to permit the connecting member to fold after the carriage has been shifted to its normal starting position.

In Figs. 5 and 6 I have illustrated a foot piece 23' which is carried by a sliding yoke 24 mounted upon the bar 25. The foot piece 23' extends laterally from the yoke and is to be engaged by the side of the foot as the foot extends transversely of the yoke 24 when in operative position. The yoke 24 is U-shaped in cross section as shown in Fig. 6, and bolts or pins 26, connect the sides thereof to retain the yoke on the bar 25.

The bar 25 has its ends connected to the up-standing end portions of a U-shaped bracket 26, adapted to be attached to the floor adjacent one leg of the desk. The foot piece has attached to the rear face thereof, a lateral arm 26, the outer end of which may be connected to the belt 13. In this form of foot piece the same is engaged by the side of the foot and moved along the bar 25 for shifting the carriage.

From the foregoing, it will be apparent that I have provided a foot accelerated carriage shift which can be used in connection with conventional types of typewriting machines for shifting the paper carriage without the operator having

to remove his hands from the key-board and the eyes from the copy.

The connecting member 16, between the finger 14, and the carriage, is of a flexible or foldable nature, so that should it be desired to shift the carriage by hand, it can be easily done without operating the foot treadle 23. The device is very simple in its construction, and can be manufactured and placed upon the market at a very low cost.

While I have shown and described the preferred embodiment of my invention, it will be understood that various changes and alterations can be made when putting the invention into practice without departing from the spirit of the invention, or the scope of the appended claim.

What I claim is:

In combination with a typewriter including a movable carriage and a support for the typewriter, a base member adjacent the support, a rotatable drum mounted upon said base, a sectional adjustable standard carried by said drum and disposed in a vertical plane, a guide bracket carried by the support and embracing the upper portion of the standard, means for retaining the upper portion of the standard against downward movement relative to the bracket, a lateral integral extension at the upper end of the standard, a finger adjustably connected to the lateral extension, and a pliable connecting unit between the finger and the carriage.

ROY C. MASTERS.
